US0D1074113S

(12) **United States Design Patent** (10) Patent No.: **US D1,074,113 S**
(45) Date of Patent: ** May 6, 2025

(54) **SAFE BOX**

(71) Applicant: **Shenzhen Huakong Technology Co., Ltd.**, Shenzhen (CN)

(72) Inventor: **Huiling Zeng**, Shenzhen (CN)

(**) Term: **15 Years**

(21) Appl. No.: **29/921,893**

(22) Filed: **Jan. 30, 2024**

(51) LOC (15) Cl. **99-00**

(52) U.S. Cl.

USPC **D99/28**

(58) **Field of Classification Search**

CLAIM

The ornamental design for a safe box, as shown and described.

DESCRIPTION

FIG. 1 is a front, bottom, and left side perspective view of a safe box, showing my new design;

FIG. 2 is a rear, top, and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate the portions of the safe box, which form no part of the claimed design.

1 Claim, 8 Drawing Sheets
